ELECTRICAL SHORT CIRCUIT TESTER

Raymond P. Smith, Jr., Williamsport, Pa., assignor to
Craftmaster, Inc., Williamsport, Pa.

Filed Oct. 30, 1973, Ser. No. 411,138

Term of patent 14 years

Int. Cl. D10—04

U.S. Cl. D10—78

FIG. 1

FIG. 2

FIG. 3

FIG. 4

FIG. 1 is a front, top and left side perspective view of an electrical short circuit tester showing my new design; FIG. 2 is a right side elevational view thereof;

FIG. 3 is a rear elevational view thereof; and FIG. 4 is a bottom plan view thereof.

I claim:

The ornamental design for an electrical short circuit tester, as shown and described.
